UNITED STATES PATENT OFFICE.

HARRY K. QUAN, OF NEW YORK, N. Y.

DESIGN FOR A BOTTLE.

Application filed February 9, 1922. Serial No. 612. Term of patent 3½ years.

To all whom it may concern:

Be it known that I, HARRY K. QUAN, a citizen of the United States, and a resident of the city of New York, borough of Manhattan, in the county of New York and State of New York, have invented a new, original, and ornamental Design for a Bottle, of which the following is a specification, reference being had to the accompanying drawings forming part thereof, in which

I claim:

The ornamental design for a bottle substantially as shown.

HARRY K. QUAN.
